WITNESS:
H. Sherburne,

UNITED STATES PATENT OFFICE.

ELI H. WIEL, OF SAN FRANCISCO, CALIFORNIA.

GAME ACCESSORY.

Application filed January 3, 1923. Serial No. 610,426.

To all whom it may concern:

Be it known that I, ELI H. WIEL, a citizen of the United States, and a resident of the city and county of San Francisco, State of California, have invented a certain new and useful Game Accessory, of which the following is a specification.

The invention relates to a device to be used in connection with games employing flat oblong pieces or men, somewhat of the shape of a domino. The device is particularly useful in playing the now popular oriental game, usually called "Mah Jong," which comprises a large number of flat-oblong pieces delineated on their faces to represent different characters and values. In this game the flat oblong domino-like pieces are called "tiles" and will be so referred to herein. The game is played by four players, who first build a rectangular wall of the tiles, each side of the wall being 18 tiles long and two tiles high. Each player draws 13 tiles from the wall, in a manner provided for in the rules of the game and sets the tiles up in front of him, so that he, and no other player, may see the face of the tiles. The players then successively draw from the wall and discard one tile, the object being to make a hand consisting of four sets of three tiles each, either three of a kind or a sequence, and one pair. The player accomplishing this first wins the game. A rather complex system of scoring forms part of the game and at the end of each game, the players pay each other, according to their respective scores, counters being used for this purpose. The counters are long narrow pieces of bone, about $2\frac{1}{2}$ inches long and $\frac{1}{4}$ of an inch wide, marked to give them different values. These counters are rather difficult to handle and their manipulation requires much time, which might otherwise be devoted to playing the game. The tiles are also quite narrow, so that a jar of the playing table often upsets them, exposing the hand to the opponent.

An object of my invention is to provide a device for facilitating the playing of the game, by providing a rack to hold the tiles drawn from the wall, so that they will not fall over and may be readily shifted and a tray to hold the counters so that they are readily accessible.

The invention possesses other advantageous features, some of which with the fore-

going, will be set forth at length in the following description, where I shall outline in full, those forms of the invention which I have selected for illustration in the drawings accompanying and forming part of the present specification. In said drawings I have shown several forms of the device embodying my invention, but it is to be understood that I do not limit myself to such forms, since the invention, as set forth in the claims may be embodied in a plurality of other forms.

Referring to said drawings:

Figure 1 is a perspective view of one form of device embodying my invention.

Fig. 2 is a perspective view of the device shown in Fig. 1, with the rack lifted to permit access to the counter tray.

Fig. 3 is a cross section of the device shown in Fig. 1.

My invention relates to a game accessory comprising a combined rack and counter tray. The device is preferably made of wood and may be painted or delineated in any suitable manner to render it ornamental and attractive. The rack 2 comprises a backwardly and downwardly inclined shelf 3 and an inclined back wall 4, perpendicular to the shelf. The shelf is substantially of the same depth as the thickness of the tiles 5, and the tiles rest on the shelf and against the back wall. The inclination of the back wall is such that the faces of the tiles are substantially perpendicular to the line of sight of the player. In Fig. 1, I have shown three tiles of the "dot" suit on the rack, but it is to be understood that there are other suits and that the racks will hold a greater number of tiles. The rack is usually made 18 tiles long so that it serves as a guide or backing in building the wall, thus obviating the necessity of counting the tiles as the walls are being built.

In the construction shown in the drawings the rack is hinged at its rear lower edge, to the rear upper edge of the counter tray 6 so that the rack serves as a cover for the tray. The tray is preferably provided with a round bottom trough 7, which is divided into a plurality of compartments by the partitions 8. The counters 9 are usually of four different denominations and the tray is preferably divided into four compartments so that the counters of different denominations may be segregated. The trough is closed

on the ends by the end walls 12 and the rack, when closed down, prevents the displacement of the counters.

By the use of a device embodying my invention, the playing of the game is greatly facilitated; the tiles are supported so that they will not fall over and the counters are kept segregated and are readily accessible.

Throughout the specification I have referred to the pieces with which the game is played as "tiles," but it is to be understood that such word is used merely for convenience and illustration and that the device is

intended to be used with any forms of pieces which are set up before the player in playing a game.

I claim:

A device for use in playing a game employing tiles and counters comprising a counter tray, a movable cover on said tray and a tile rack consisting of an inclined shelf and an inclined back wall substantially perpendicular to the shelf, on said cover.

In testimony whereof, I have hereunto set my hand.

ELI H. WIEL.
